UNITED STATES PATENT OFFICE.

WILLIAM F. LAUTENSCHLAGER, OF CINCINNATI, OHIO.

PERFORATING-MACHINE.

1,176,472.

Specification of Letters Patent.

Patented Mar. 21, 1916.

Application filed December 23, 1915. Serial No. 68,347.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Perforating-Machines, of which the following is a specification.

My invention relates to perforating machines adapted for providing the parts of shoe uppers, harness, saddlery goods and the like, with perforations, and the invention relates particularly to novel means whereby the facility for placing, feeding and handling the material is enhanced.

It is the object of my invention to provide novel means whereby closed margins may be readily so placed with relation to the punch and the gage as to locate the gage within the closed margin, and further to provide novel means whereby the material having the closed margin may be laid substantially flat upon the material-support and guided in substantially flat relation around the gage and under the punch.

It is the object of my invention, further, to provide a perforating machine with a shiftable gage for the material, past which the material of the closed margin may be slipped, for placing the closed margin to be perforated about the gage, the closed margin being then guided continuously throughout its closed path against the gage and lengthwise past the reciprocating punch, and further to provide the perforating machine with a gage and a hold-down finger for shifting the gage relative to the hold-down finger for passage of the material past the gage in a direction reverse to the direction in which the edge thereof is presented to the gage during the punching operation.

It is the object of my invention, further, to provide a perforating machine with a hold-down finger and a resiliently yieldable gage for the material adjacent to the hold-down finger, so arranged that the gage will yield with relation to the hold-down finger by pressure thereon of the material while moving the material past the gage into range with the punch.

The invention will be further readily understood from the following description and claims, and from the drawings, in which latter:

Figure 1 represents a side elevation of so

much of a perforating machine as is necessary to illustrate my invention. Fig. 2 is a head-end elevation of the same showing the table and frame partly in section on the line 2—2 of Fig. 1. Fig. 3 is a rear elevation of the head-end of the machine, partly broken away. Fig. 4 is a plan view showing my improved device employed in perforating a closed vamp, the punch, gage, hold-down finger and presser-foot being partly broken away. Fig. 5 is a side elevation, partly broken away, showing the normal relations between the gage, hold-down finger and punch when about to enter a piece of material under the gage; the table, cushion-strip and material being shown in vertical section on the line 5—5 of Fig. 2. Fig. 6 is a similar view of the parts showing their relations with the material entered under 75 the gage. Fig. 7 is a similar view of the parts, showing the edge of the margin to be punched against the gage under the hold-down finger. Fig. 8 is a front elevation of the gage. Fig. 9 is a detail of the same 80 shown in front elevation. Fig. 10 is a horizontal section of the same taken on the line 10—10 of Fig. 7. Fig. 11 is a vertical sectional detail of the same on the line 11—11 of Fig. 5. Fig. 12 is a detail of the same in 85 horizontal section on the line 12—12 of Fig. 5. Fig. 13 is a bottom view of the table showing the means for guiding the cushion-strip; and Fig. 14 is a vertical section of the same taken on the line 14—14 of Fig. 13. 90

I have exemplified my improvement as applied in a perforating machine such as shown and described in Letters Patent No. 843,899, issued to me February 12, 1907, for improvements in punching machines.

There is a frame 11, which has an arm 12 projecting therefrom, in which there are bearings 13 having rods 14 secured therein. A punch-ram head 15 has bearings 16 slideable on the rods 14, suitable means being 100 provided, for instance as shown and described in said aforesaid patent for laterally reciprocating the punch-ram head.

There is a punch-arm 17, in the lower end of which a suitable punch 18 is arranged to be 105 releasably secured. The ram is reciprocated up and down in bearings 19 on the punch-ram head by suitable means, for instance as exemplified in my aforesaid patent.

The punch is arranged to co-operate with 110 an anvil 21, exemplified as in a work-supporting table 22 supported on the frame, the

parts having a material-supporting surface 23 for the material 24, represented as a closed vamp.

A presser-foot 25 is secured to a rod 26 5 slidable in bearings 27, wherein the rod is prevented from turning. The presser-foot is arranged to be reciprocated up and down in consonance with the retracting movements of the punch, instanced as a feeding 10 punch, so as to hold the material in place while the punch is retracted to initial position prior to a subsequent feeding movement. The presser-foot is also arranged to be manually raised, as by means of an arm 15 28 connected in suitable manner with a treadle suitably disposed, as in said patent mentioned.

The arm 28 is secured to a rock-shaft 31 journaled in the frame. This rock-shaft has 20 an arm 32 secured thereto, which contacts a bracket 33 adjustably secured to the rod 26, whereby, upon rocking of the rock-shaft 31 by means of the treadle, the rod 26 and the presser-foot 25 are raised off the material. The parts hereinbefore mentioned 25 may all be constructed, mounted and operated in manner described in my aforesaid patent.

If desired, a cushion-strip 38, which may 30 be a strip of paper, as explained in said patent, may be interposed between the cutting edges of the punch and the anvil.

In operation in the present exemplification of my invention, the punch descends 35 into the material, firmly against or into the cushion-strip, then slightly rises, moves in the feeding movement of the punch for feeding the material above and with relation to the cushion-strip, then slightly descends, 40 and then rises out of the material and retracts to initial position, as shown and described in my aforesaid patent. A slight feeding movement may be imparted to the cushion-strip, which may be accomplished 45 by means of a feed-wheel 39 coacting with an impact-face 40, the feed-wheel being intermittently operated as shown and described in my aforesaid patent.

The cushion-strip is arranged to be received off a suitable supply-roll across a ledge 41 on an adjustable guide-plate 42 having guide-lugs 43 thereon contacting the edges of the strip for guiding its path.

A tension-bar 44 is arranged to press upon 55 the cushion-strip for retarding its forward movement. The tension-bar has a finger-piece 45 thereon. The guide-plate has a finger-piece 46 thereon extending from the ledge 41. A pivot-pin 47 is secured in a lug 60 48 at the bottom of the table and passes through bearing holes in the tension-bar and guide-plate. A spring 49 about the pivot-pin bears on the tension-bar for pressing the same toward the guide-plate and thereby 65 pressing upon the cushion-strip, the spring

being adjustable by a nut 50 on the pivot-pin.

The guide-plate is provided with a slot 54 and the tension-bar is provided with a hole 55 of larger diameter than the width 70 of the slot. A clamp-bolt 56 passes through the hole 55 and has a shoulder 57 which bears upon the walls of the slot 54, the clamp-bolt being threaded into a lug 58 on the lower face of the table. 75

The cushion-strip passes through an inclined slot 61 in the table, across the anvil, and through an inclined slot 62 in the table, about a lug 63 at the bottom of the table, and between the feed-wheel 39 and its co- 80 acting impact-face 40, the cushion-strip extending in the direction of feeding movement of the material.

The slots 61 and 62 are sufficiently wide to receive varicus widths of cushion-strips 85 and permit lateral adjustment of the cushion-strips therein. If it is desired to adjust the cushion-strip laterally, the clamp-bolt 56 is turned for releasing the guide-plate, which is shifted on its pivot 47 by means of the finger-piece 46, whereby the guide-lugs 43 are shifted laterally for controlling the path of the cushion-strip. When the guide-plate is in adjusted position, the clamp-bolt 90 is again clamped upon the adjustable plate. 95 The cushion-strip is readily placed between the guide-plate and the tension-bar by depressing the tension-bar by means of the finger-piece 45.

In perforating closed margins, for instance the upper margins of closed vamps, it has been a usual practice heretofore in machines of this character to cause the margin to be guided in a path parallel with the feeding movement and so as to follow the 100 curves of the margin, with the entire closed margin located at one side of the punch-ram, which position would be to the left of the punch-ram exemplified in Fig. 1. The handling of the closed vamp while perforating the same, manipulated in this manner, has been found to be extremely difficult and cumbersome, especially when perforating 110 around the throat of the vamp.

I have found that by providing a shiftable gage I am enabled to cause a stretch of the closed vamp to pass the gage into punching position for locating the closed margin around the gage, that is to say, inclosing the gage by the closed margin, such a relation 115 of parts being exemplified in Fig. 4. I have, therefore, provided a shiftable gage 66 having a guiding face 67, against which the edge 68 of the material is arranged to be guided during the perforating operation. 120 This edge is exemplified as a folded edge. The shiftable gage is exemplified as pivot- 125 ed by means of a pivot 69 to a depending bracket 70 secured to the arm of the machine. The bracket is adjustable on the arm, 130

as by having a clamp-bolt 71 threaded into a lug 72 of the arm and passing through a slot 73 in the bracket, there being a tongue and groove guide-connection 74 between the bracket and lug. A set-screw 75 is threaded into a lug 76 of the bracket and impinges the lug 72.

A spring 78 is arranged to resiliently retract the gage when shifted out of normal position, the normal position being preferably against the material-supporting surface. The spring is shown clamped to the bracket by means of a clamp-screw 79 at one of its ends, the other end of the spring having sliding movement in a slot 80 in the gage.

A hold-down finger 81 is arranged to hold down the edge of the material being perforated and is exemplified as adjustable toward and from the material-supporting surface, so as to permit different thicknesses of material to readily pass thereunder. It is preferably of spring material and is shown clamped to the bracket by means of the clamp-screw 79. A set-screw 82 is threaded in the bracket 70 and bears against the shank of the hold-down finger for raising or lowering the material-engaging portion of the hold-down finger. Lateral movement of the hold-down finger is preferably limited by a pin 83 in the bracket 70 received in a slot 84 in the hold-down finger.

The gage is preferably shiftable by means of the material, accomplished in the present exemplification by providing the rear of the gage with a contact-face 85, shown inclined upwardly and rearwardly from the bottom of the gage, the construction being such that when the body of the material whose margin is to be perforated is moved past the gage toward the punch, that is, in a direction reverse to the direction in which the edge to be perforated is moved toward the guiding-face 67 during the perforating operation, the outer edge 86 of the material will contact the inclined contact-face and thereby raise the gage for permitting the body of the material to be shifted thereunder past the gage, so that the margin to be perforated will be brought into range of the reciprocating punch and under the projecting end of the hold-down finger.

I have exemplified the relation of the parts in Figs. 5, 6 and 7, Fig. 5 representing the relation of the parts as the outer edge of the material is about to be brought into contact with the contact-face of the gage by movement of the body of the material in the direction of the arrow *a*, Fig. 5 showing the relation of the parts after the body of the material has been brought under the gage, and Fig. 7 representing the relation of the parts after the edge of the material to be perforated has been moved to contact the guiding-face 67 for being guided thereby,

usually effected by a movement of the material in a direction reverse to the direction indicated by the arrow *a*, the presser-foot and the punch during such movements of the material being in raised positions.

70

Under employment of my invention, materials having closed margins, for instance closed vamps, are readily manipulated by the operator for feeding the closed margin past the gage and for having the material 75 adjacent to the punch, especially at the throat of the vamp, lie smoothly upon the material supporting surface, such a relation being exemplified in Fig. 4.

In perforating the closed vamp, it is laid 80 with its outer face upward upon the material-supporting surface, and one portion of its body, for instance at one side of the back-seam, is presented with its outer edge 86 toward the rear contact-face 85 of the 85 gage, and slipped under and past the gage, which is raised thereby, its inner edge being then presented toward the guiding-face of the gage, and the perforating begun at one side of the back-seam, and continued around 90 the entire upper margin of the closed vamp to the point of beginning, substantially all portions of the vamp being substantially flat upon the material-support during the entire perforating operation, the vamp when 95 perforated, being again slipped under the gage for removing the same, the gage yielding upon contact of the inner edge 68 of the vamp with the rear contact-face of the gage. The operation is quickly performed and the 100 feeding of the closed vamp readily accomplished.

The gage and hold-down finger are represented in adjacent positions, the gage being shiftable with relation to the hold-down 105 finger in perpendicular manner with relation to the material-supporting surface, for permitting the material to pass the gage while under the hold-down finger.

Having thus fully described my invention, what I claim as new and desire to secure by Letters Patent, is:

1. In a perforating machine, the combination with an anvil and a reciprocating punch-ram arranged for having a punch attached thereto, of a gage for the edge of the material, a hold-down means for the material, and means for movement of said gage with relation to said hold-down means for movement of the body of the material past 115 said gage for placing its edge in range with said gage and said reciprocating punch.

2. In a perforating machine, the combination of a material-support, a reciprocating punch, a gage having a guiding face 120 presented toward said punch, a hold-down means for the material, and means for movement of said gage in perpendicular manner with relation to said material-support for passage of the material past said gage to 125

130

ward said punch into range of said reciprocating punch and under said hold-down means.

3. In a perforating machine, the combination with a material-support, and a reciprocating punch, of a gage having a guiding face for the edge of the material, a hold-down finger for said edge, means for pivoting said gage whereby said gage is moved by contact of the material therewith during movement of said material past said gage into range of said punch, and a spring for normally returning said gage to normal position with its guiding face presented toward said punch adjacent to the plane of said material-support.

4. In a perforating machine, the combination of an anvil, a reciprocating punch-ram, a hold-down finger for the material, and a gage for the material, said hold-down finger and gage located in adjacent positions, and said gage resiliently yieldable for the passage of a stretch of the material past said gage under said hold-down finger.

5. In a perforating machine, the combination of an anvil, a reciprocating punch-ram, a hold-down finger, a gage having a guiding-face for the edge of the material, and means for mounting said gage for resilient yield of said gage by contact of the material for the passage of a stretch of the material past said gage for presenting the edge thereof to be perforated toward said guiding-face and under said hold-down finger.

6. In a perforating machine, the combination of a reciprocating punch-ram, a cushion-strip arranged to receive the blows of the punch and to be fed, and a gage for the edge of the material at the side of said cushion-strip mounted for yielding automatically by pressure of the material.

7. In a perforating machine, the combination of a reciprocating punch-ram, a cushion-strip arranged to receive the blows of the punch and to be fed, a gage for the edge of the material mounted for yielding automatically by pressure of the material, and means for adjusting the lateral relation between said cushion-strip and said gage.

8. In a perforating machine, the combination of a reciprocating punch-ram, a cushion-strip arranged to receive the blows of the punch and to be fed, a gage for the edge of the material at the side of said cushion-strip mounted for yielding automatically by pressure of the material, and means for adjusting said gage toward and from said cushion-strip.

9. In a perforating machine, the combination with a punch-ram, of a gage having a guiding-face for the edge of the material and a face arranged to be contacted by the material for causing yielding of the gage by pressure of the material thereon.

10. In a perforating machine, the combination of a material-support, a reciprocating punch-ram, and a gage for the edge of the material at the side of said punch-ram yieldable by pressure thereon in a direction toward the punch-ram.

11. In a perforating machine, the combination with an anvil and a reciprocating punch-ram, of a gage for the edge of the material yieldable by pressure reversely to the direction in which the edge of the material is presented to the gage when perforating said edge.

12. In a perforating machine of the character described, the combination with an anvil and a reciprocating punch-ram, of a gage having a guiding-face for the edge of the material, and means whereby said gage is resiliently yieldable by pressure of the material in a direction reverse to that in which said edge is presented to said guiding-face during the perforating operation.

13. In a perforating machine for perforating the upper margins of closed vamps, the combination with an anvil, and a reciprocating punch-ram, of a gage having a guiding face for the edge of said margin, and means for resilient yielding of said gage by movement of the material of the vamp across said gage in a direction reverse to the direction in which said edge is presented toward said guiding face, whereby said upper edge of said margin is caused to surround said guiding-face.

14. In a perforating machine for perforating the upper margins of closed vamps, the combination with an anvil and a reciprocating punch-ram, of a gage having a guiding-face for the edge of said upper margin, a hold-down finger for said margin, and means for mounting said gage whereby said gage is yieldable with relation to said hold-down finger by contact of the material of said vamp and movement of said material toward said punch-ram.

15. In a perforating machine for perforating the upper margins of closed vamps, the combination with an anvil and a reciprocating punch-ram, of a gage for the edge of said upper margin located at the side of the path of movement of said punch-ram, and means for resilient yielding of said gage by movement of the material across said gage toward the path of movement of said punch.

16. In a perforating machine for perforating the upper margins of closed vamps, the combination with an anvil and a reciprocating punch-ram, of a gage for the edge of said upper margin located at the side of the path of movement of said punch-ram, and means for resilient yielding of said gage by movement of the material across said gage toward the path of movement of said punch, and a hold-down finger for said edge.

with relation to which said gage is yieldable.

17. In a perforating machine, the combination of a frame, an anvil supported thereby, an arm projecting from said frame above the plane of said anvil, a reciprocating punch-ram on said arm, a gage depending from said arm into adjacency with said anvil, said gage having a guiding-face for 10 the edge of the material, and means for resiliently yieldingly supporting said gage, whereby said gage is resiliently moved by movement of the material past said guiding-face toward said punch-ram.
18. In a perforating machine of the character described, the combination of a frame, a reciprocating punch-ram, a material-sup-

port, an arm projecting above said material-support on which said punch-ram is mounted, a depending bracket extending from said arm, a hold-down finger supported thereby, a gage for the edge of the material pivoted to said bracket, means for resiliently holding said gage toward said material-support, and means for adjusting the said hold-down finger toward and from said material-support. 20 25

In testimony whereof, I have hereunto signed my name in the presence of two subscribing witnesses.

WILLIAM F. LAUTENSCHLAGER.
